US00D945416S

(12) **United States Design Patent** (10) **Patent No.:** **US D945,416 S**
(45) **Date of Patent:** **** Mar. 8, 2022**

(54) **MEDIA STREAMING ACCESSORY**

(71) Applicant: **GOOGLE LLC**, Mountain View, CA (US)

(72) Inventors: **Stefan Reichert**, Mountain View, CA (US); **Henry A. Beyer**, San Francisco, CA (US); **Maj Isabelle Olsson**, Sunnyvale, CA (US); **Katherine Morgenroth**, Los Gatos, CA (US)

(73) Assignee: **GOOGLE LLC**, Mountain View, CA (US)

(**) Term: **15 Years**

(21) Appl. No.: **29/737,185**

(22) Filed: **Jun. 5, 2020**

(51) LOC (13) Cl. **14-02**

(52) U.S. Cl.

USPC **D14/356**

(58) **Field of Classification Search**

USPC ... D13/133, 154, 158, 162.1, 162, 168, 171, D13/184; D14/125–134, 155, 167–168, D14/188, 203.1, 203.3, 217–218, 238.1, D14/299, 356–358, 388, 400–401, 433, D14/435.1, 454, 480.1, 480.2, 480.3, D14/480.4, 496; D21/332; D9/432

(57) **CLAIM**

The ornamental design for a media streaming accessory, as shown and described.

DESCRIPTION

FIG. 1 is a front perspective view of a media streaming accessory showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines illustrate portions of the media streaming accessory that forms no part of the claimed design.

1 Claim, 5 Drawing Sheets
